[57] CLAIM

The ornamental design for an apparatus kit for making bias strips, as shown and described.

DESCRIPTION

FIG. 1 is a perspective view of an apparatus kit for making bias strips of the first embodiment showing my new design. The other three embodiments being identical except for the width of the centrally disposed depression and the width of the template;

FIG. 2 is a front elevational view of embodiment 2;
FIG. 3 is a front elevational view of embodiment 1;
FIG. 4 is a front elevational view of embodiment 3;
FIG. 5 is a front elevational view of embodiment 4;
FIG. 6 is a rear elevational view of embodiment 2;
FIG. 7 is a rear elevational view of embodiment 1;
FIG. 8 is a rear elevational view of embodiment 3;
FIG. 9 is a rear elevational view of embodiment 4;
FIG. 10 is a top view of embodiment 2;
FIG. 11 is a top view of embodiment 1;
FIG. 12 is a top view of embodiment 3;
FIG. 13 is a top view of embodiment 4; and,
FIG. 14 is a typical right side elevational view, with the left side elevational view being a mirror image thereof.
